UNITED STATES PATENT OFFICE.

JULES D. BISCAYART AND FERNAND CAILLETEAU, OF ATLANTA, GEORGIA.

DEVICE FOR OPERATING SNAP-SWITCHES.

1,264,761.

Specification of Letters Patent. Patented Apr. 30, 1918.

Application filed August 14, 1917. Serial No. 186,247.

To all whom it may concern:

Be it known that JULES D. BISCAYART and FERNAND CAILLETEAU, citizens of the United States, residing at Atlanta, in the county of 5 Fulton and State of Georgia, have invented certain new and useful Improvements in Devices for Operating Snap-Switches; and they do hereby declare the following to be a full, clear, and exact description of the 10 invention, such as will enable others skilled in the art to which it appertains to make and use the same, reference being had to the accompanying drawings, and to the letters and figures of reference marked thereon, 15 which form a part of this specification.

This invention relates to new and useful improvements in attachments to buttons of snap switches, affording a convenient means for attachment thereto and consists of a 20 single cord operated device, having various details of construction, combinations and arrangements of parts which will be herein-after fully described, shown in the accompanying drawings and then specifically defined in the appended claim.

The invention is illustrated in the accompanying drawings which, with the letters of reference marked thereon, form a part of this specification and in which:

30 Figure 1 is a view in elevation showing the application of our invention to a switch button.

Fig. 2 is an elevation of the inner face of the device.

35 Fig. 3 is a cross sectional view on line 3—3 of Fig. 2.

Fig. 4 is a detailed view showing a slight modification of the invention.

Reference now being had to the details of 40 the drawings by letter:

A designates a plate of any suitable material and which is of general oblong shape having a contracted portion A' bent at an angle and apertured for the reception of a 45 cord or chain B, provided for the purpose of tilting the plate in one direction.

Said plate has a marginal flange B' projecting laterally therefrom and lugs C are struck up from said flange at one end of 50 the plate and coöperate with other lugs, designated by letter D, also struck up from the plate at right angles thereto to retain the weighted member E between the flanges and in the position shown in the drawings.

55 Said plate has a circular outlined opening F formed therein, and H is a ratchet wheel

having a central raised circular outlined portion H' which is journaled in the said opening and lugs I are struck up from the flanges and are bent at right angles thereto 60 and serve to retain the ratchet wheel within the opening forming a bearing therefor. Said circular outlined raised portion of the ratchet wheel is provided with an elongated slot, designated in the drawings by letter 65 K, and L is the button clutch member, bent substantially U shape and extending through said slot. Said member L has laterally extending lugs L' which are bent at right angles at a point designated by letter L² 70 and passing through slots H² formed in the circular outlined portion of the ratchet wheel and which serve to securely anchor the clutch member to the ratchet wheel. Said ratchet wheel has laterally extending 75 fingers O parallel to each other and which fingers have angled lugs O' projecting from the edges thereof and which are adapted to engage over the ends of a switch button to securely anchor the clutch member to the 80 button. A pawl, designated by letter T has pintles projecting therefrom which are pivotally mounted in a lug S integral with the flange of the plate and in an aperture in the latter, said pawl being adapted to engage 85 the teeth of the ratchet wheel. Said pawl, it will be noted, has a laterally projecting lug T' guided in the slot A² formed in the plate and which serves to limit the outer throw of the pawl.

90 In the modified form, shown in Fig. 4 of the drawings, it will be noted that instead of the pivotal pawl shown in Fig. 2 of the drawings, a lug W is shown as struck up from the plate and which serves as a pawl, 95 said lug W serving to engage the teeth when moving in one direction and turns idly over the same when moving in the opposite direction, otherwise the modified form embodies the same construction as disclosed in Fig. 100 2 of the drawings. Upon reference to Fig. 4 of the drawings, it will be noted that the marginal edge of the opening in which the ratchet wheel is journaled, is designated by dotted lines, and that a space intervenes between the marginal edge of the struck-up portion H' and the circular dotted line and which will permit the wheel to turn idly, by reason of a lateral or wobbling movement, which will be imparted to the wheel 110 as the ratchet teeth come in contact with said pawl.

In operation, the clutch member is fastened to the button of a switch by bending the fingers and lug over the edge of the button, as shown, and normally the weighted member holds the plate in the position shown in Fig. 1 of the drawings. When desired to turn the switch button the operator, by pulling upon the cord, will cause the ratchet wheel to be given a partial rotary movement by the pawl engaging the teeth thereof, thus causing the button to turn. When the cord is released, the weight will cause the plate to return to its normal position, the pawl turning idly over the ratchet wheel.

What we claim to be new is:—

An attachment for turning switch buttons, comprising a plate having a circular outlined opening therein, a weighted member mounted upon one end of the plate, and

a cord connected to the plate at the end opposite the weighted member, a ratchet wheel having a circular outlined struck up portion journaled in the side opening, said ratchet wheel having an elongated slot therein, a button clutch member engaging said slot and having fingers for attachment to the button of a switch, means for fastening said member to said wheel, a pawl pivotally mounted upon the plate and having a laterally extending lug movable in a slot in the plate. 25 30

In testimony whereof we hereunto affix our signatures in presence of two witnesses.

JULES BISCAYART.
FERNAND CAILLETEAU.
